UNITED STATES PATENT OFFICE.

ROBERT O. VANDERCOOK, OF CHICAGO, ILLINOIS.

PROOF PRINTING-PRESS.

992,461.

Specification of Letters Patent. Patented May 16, 1911.

Application filed September 9, 1909. Serial No. 516,912.

To all whom it may concern:

Be it known that I, ROBERT O. VANDERCOOK, a citizen of the United States, and a resident of Chicago, in the county of Cook 5 and State of Illinois, have invented certain new and useful Improvements in Proof Printing-Presses, (Case A;) and I do hereby declare that the following is a full, clear, and exact description thereof, reference being had to the accompanying drawings, and 10 to the letters of reference marked thereon, which form a part of this specification.

This invention relates to a novel printing press adapted to take proof impressions from 15 forms of type, linotypes, electro-types, cuts, engravings or other printable forms used with printing presses, and the invention consists of the matters hereinafter fully described and more specifically pointed out in 20 the appended claims.

The invention relates particularly to the type of proof printing press described in an application filed by me on February 8th, 1909, Serial No. 476,695, and to a certain 25 novel and improved construction by means of which the impression member, while being properly held down to its work when traveling in a forward direction to make the impression, as described in said prior application, is lifted upon its return trip so as not 30 to engage the faces of the type or of the proof sheet. Said impression member travels back to its initial position in this elevated plane where it is again brought into a 35 plane to engage the type and make proof impression in its forward movement. The press is also provided with an improved mechanism which prevents any possibility of the disengagement of the segmental gear- 40 teeth from the racks in which they travel, all of which will be more fully described in the following specification.

In the drawings:—Figure 1 is a vertical, longitudinal section through a proof printing press of the type described, provided 45 with the novel features above referred to with the impression member at the end of its path after taking an impression. Fig. 2 is a top plan view of the same showing the impression member at the middle of its path as 50 it is taking an impression. Fig. 3 is a similar sectional view of the bed and of the impression member with the latter in its initial position. Fig. 4 is a similar view showing 55 the impression member when in active position making a proof impression. Fig. 5 is

a partial vertical section through Fig. 2 on the line 5—5 thereof. Fig. 6 is a side elevation of the impression member showing the segmental gears by which it is operated. 60

In the drawings, 1 indicates the bed-plate of the machine supported on suitable legs 2, 2 and provided with vertically arranged, parallel side plates or brackets 3, 3 which are arranged parallel with the path of the impression-member and support the rails which 65 control the operation of the impression member.

1^a indicates the type or other form supported on the bed and 1^b the proof sheet 70 superposed on the type (see Fig. 5).

4 indicates the impression-member which comprises a segmental, cylindric body or platen 5 of a length substantially equal to the width of the bed-plate 1, a radially arranged web 6, preferably made integral therewith, cylindric bearing surfaces 5^a at the opposite ends of the impression-member, and segmental gears 7, 7 arranged at each end of and rigidly secured thereto. Mounted 75 concentrically with the axes of said bearing surfaces and of the segmental gears are hubs 8, 8 in which are secured short stub axles or shafts 9, 9 which are provided with rollers 10, 10. The stub shafts may be made either 80 integral with the platen or separately 85 from it.

11, 11 indicate downwardly facing rails carried on the brackets 3, 3. Said rails hold the impression-member down to its work 90 with the bearing surfaces 5^a, 5^a in contact with bearing rails 12^a, 12^a formed at each side of the bed 1, and maintain the teeth of the segmental gears in contact with racks 12, 12, formed adjacent said bearing rails 95 (see Figs. 4 and 5).

13, 13 indicate socketed lugs formed at each end of the web 6 for the attachment of an operating arm or bar 16.

So far the machine is practically as described in the application referred to and forms no part of the present invention. 100

14, 14 indicate supporting rails secured to the inner faces of the brackets 3, 3 in a position parallel to the rails 11, 11 and located nearer the faces of said brackets than are the rails 11, 11 by a distance equal to a little more than the width of the rollers 10, 10. Said rails are vertically spaced below the rails 11, 11 a distance slightly less 110 than the diameters of the rollers 10, 10. The upper faces of said rails are curved down-

wardly at their ends, as indicated at 15, 15, (see Figs. 1 and 4).

The rollers 10, are loosely mounted on the stub shafts 9, 9 so as to have both rotatable and endwise movement thereon. At the forward ends of the brackets 3, 3, are arranged cam plates 17, 17 which, when the impression member reaches the end of the path of its travel, are adapted to engage the inner faces of the rollers 10, 10 and withdraw them toward the brackets 3, 3 away from their contact with the downwardly facing tracks 11, 11. This movement brings them into line with the rails 14, 14, so that when the impression member is rocked forward to its initial position the rollers 10, 10 engage the downwardly curved portions 15, 15 of the supporting rails 14, 14 and travel back to their initial position on the rails 14, 14 (as illustrated in dotted lines in Fig. 1). This raises the impression-member from a position of contact with the type, or the proof sheet superposed thereon. At the other end of the bracket plates 3, 3 are arranged cam plates 18, 18 which are adapted, when the impression-member approaches its initial position, to engage the ends of the roller hubs and push them back into their former position ready to be engaged by the downwardly facing rails 11, 11—the downward curves of the rails at 15, 15 permitting the lowering of said rollers sufficiently for them to be pushed under the faces of said rails. The vertical distance between the downwardly facing rails 11, 11 and the supporting rails 14, 14 is just sufficient for the impression-member to be lifted out of its engagement with the type or the proof sheet and not enough to remove the segmental gears from their active engagement with the racks 12, 12.

At each side of the forward end of the bed plate are provided upstanding angular buffers 19, 19 having projecting curved ends 19^a which are adapted, near the end of the movement forward of the impression-member, to engage pins 23, 23 secured to lugs 20, 20 formed on the outer faces of the segmental gears 7, 7, (as indicated in Fig. 6) and hold the ends of the bearing surfaces 5^a, 5^a in engagement with the bearing rails 12^a, 12^a as the impression-member swings on said ends as centers and after the rollers 10, 10 have passed beyond the limits of the rails 11, 11. This prevents the segmental gears from becoming disengaged from their respective racks and prevents the rack or gear teeth from being broken where the impression member is quickly rocked to the limit of its movement. To supplement the action of said buffers, lugs 24, 24 are formed at the forward ends of the rails 11, 11 and are adapted to be engaged by elastic disks 22, 22 secured to lugs 21, 21 formed on the faces of the segmental gears 7, 7. Pins 23^a, 23^a are located adja-

cent said elastic disks in position to engage the under side of the lugs 24, 24. There are also formed on said segmental gears, lugs 30, 30 which engage under the lugs 24, 24, when the impression member reaches the forward limits of its movement. The pins 23, 23 and similarly arranged elastic disks 22^a, 22^a, and curved lugs 30^a, 30^a perform similar functions by engagement with lugs 24^a, 24^a and with the underside of the rails 11, 11 and with angular buffers 19^b having projecting curved arms 19^c when the impression member is at the opposite limit of its movement.

25, 25 indicate elastic buffers secured in any convenient manner to the brackets 3, 3 in position to be engaged by the rollers 10, 10 and receive the shock of the impression-member at the end of its forward movement.

While I have shown herein certain details of construction and arrangement it is to be understood that I do not thereby limit my invention as it is apparent that they may be variously modified without departing from the spirit of the invention.

I claim as my invention:—

1. A printing press comprising a horizontal type-bed, a rocking, cylindric impression-member, supporting rockers on the impression-member having curved bearing surfaces concentric with the bearing surface of the impression-member, upwardly facing supporting bearing surfaces formed on the bed and adapted to be engaged by the supporting rockers, rollers carried by said rockers with their axes coincident with the axes of said rockers, downwardly facing tracks supported on said bed adapted to engage the tops of said rollers in one movement of said impression-member, upwardly facing tracks located below said downwardly facing tracks and supported from said bed and adapted to engage the rollers in the opposite movement of said impression-member, said upwardly facing tracks being adapted to lift the impression-member from its operative level, and means for shifting the relative positions of said rollers and of said upwardly and downwardly facing tracks.

2. A printing press comprising a horizontal type-bed, a rocking, cylindric impression-member, supporting rockers on the impression-member having curved bearing surfaces concentric with the bearing surfaces of the impression-member, upwardly facing supporting bearing surfaces formed on the bed and adapted to be engaged by the supporting rockers, rollers carried by said rockers with their axes coincident with the axes of said rockers, downwardly facing tracks supported on said bed adapted to engage the tops of said rollers in one movement of said impression-member, upwardly facing tracks located below said downwardly facing tracks and supported from said bed and adapted to

engage the rollers in the opposite movement of said impression-member, said upwardly facing tracks being adapted to lift the impression-member from its operative level, 5 and means for automatically shifting the relative positions of said rollers and of said upwardly and downwardly facing tracks.

3. A printing press comprising a horizontal type-bed, a rocking impression-member, 10 supporting segmental gears secured to said impression-member, racks mounted on said bed adapted to be engaged by said segmental gears, rollers carried by said impression-member with their axes coincident with the 15 axes of said segmental gears, downwardly facing tracks supported on said bed adapted to engage the tops of said rollers in one movement of said impression-member, upwardly facing tracks located below said 20 downwardly facing tracks and supported on said bed adapted to engage the under side of said rollers in the opposite movement of said impression-member, said upwardly facing tracks being adapted to lift the impression-member from its operative level, and 25 means for automatically shifting the relative position of said rollers and of said upwardly and downwardly facing tracks.

4. In a printing press comprising a horizontal type-bed, a rocking impression-member, 30 supporting segmental gears secured to said impression-member with their axes coincident with the axes of said impression-member, racks formed on the bed adapted to be engaged by said segmental gears, rollers carried by said segmental gears with their axes coincident with the axes of said segmental gears, said rollers having both 35 rotative and endwise movement with reference to said segmental gears, downwardly facing tracks supported on said bed adapted to engage the tops of said rollers in one movement of said impression member, upwardly facing tracks supported on said bed and adapted to engage the under sides of said 40 rollers in the opposite movement of said impression member, said two pairs of tracks being arranged in different vertical planes, cams supported on said bed at the opposite 45 ends thereof adapted to produce endwise movement of said rollers to bring them into engagement with one or the other of said sets of tracks, and means for limiting the 50 rocking movement of said impression member.

5. A printing press comprising a horizontal type-bed, a rocking impression-member, 55 supporting rockers on the impression-member having bearing surfaces concentric with the bearing surface of the impression member, upwardly facing supporting bearing 60 surfaces formed on the bed adapted to be engaged by said supporting rockers, rollers carried by said rockers with their axes coincident with the axes of said rockers, downwardly facing tracks supported on said bed 65 adapted to engage the tops of said rollers,

buffers formed at the end of said bed provided with projecting arms having downwardly facing surfaces, and lugs secured to the faces of said rockers adapted to be engaged by the arms of said buffers at the end 70 of the movement of said impression member.

6. A printing press comprising a horizontal type-bed, a rocking impression member, supporting segmental gears secured to said impression member, racks mounted on said bed adapted to be engaged by said segmental gears, rollers carried by said impression-member with their axes coincident with the axes of said segmental gears, downwardly facing tracks supported on said bed adapted 75 to engage the tops of said rollers, buffers formed at the end of said bed provided with projecting arms having downwardly facing surfaces, and pins secured to the faces of said segmental gears adapted to be engaged 80 by the arms of said buffers at the end of the movement of said impression member.

7. In a printing press comprising a horizontal type-bed, a rocking impression-member, supporting segmental gears secured to 90 said impression-member with their axes coincident with the axes of said impression-member, racks formed on the bed adapted to be engaged by said segmental gears, rollers carried by said segmental gears with their axes coincident with the axes of said segmental gears, said rollers having both 95 rotative and endwise movement with reference to said segmental gears, downwardly facing tracks supported on said bed adapted to engage the tops of said rollers in one movement of said impression member, upwardly facing tracks supported on said bed and adapted to engage the under sides of said 100 rollers in the opposite movement of said impression member, said two pairs of tracks being arranged in different vertical planes, cams supported on said bed at the opposite 105 ends thereof adapted to produce endwise movement of said rollers to bring them into engagement with one or the other of said sets of tracks, and means for limiting the 110 rocking movement of said impression member.

8. In a printing press comprising a horizontal type-bed, a rocking impression-member, supporting segmental gears secured to 115 said impression-member with their axes coincident with the axes of said impression-member, racks formed on the bed adapted to be engaged by said segmental gears, rollers carried by said segmental gears with their axes coincident with the axes of said segmental gears, said rollers having both 120 rotative and endwise movement with reference to said segmental gears, downwardly facing tracks supported on said bed adapted to engage the tops of said rollers in one movement of said impression-member, upwardly facing tracks supported on said bed 125 130

and adapted to engage the under sides of said rollers in the opposite movement of said impression member, said two pairs of tracks being arranged in different vertical planes, cams supported on said bed at the opposite ends thereof adapted to produce endwise movement of said rollers to bring them into engagement with one or the other of said sets of tracks, plates secured to the outer faces of said segmental gears, and lugs supported above said bed adapted to be struck by said plates at the limit of the rocking movement of said impression-member.

9. A printing press comprising a horizontal type-bed, a rocking, cylindric impression-member, supporting rockers on the impression-member having curved bearing surfaces concentric with the bearing surface of the impression-member, upwardly facing supporting bearing surfaces formed on the bed and adapted to be engaged by the supporting rockers, rollers carried by said rockers, downwardly facing tracks supported on said bed adapted to engage the tops of said rollers in one movement of said impression-member, upwardly facing tracks located below said downwardly facing tracks and supported from said bed and adapted to engage the rollers in the opposite movement of said

impression-member, said upwardly facing tracks being adapted to lift the impression-member from its operative level, and means for shifting the relative positions of said rollers and of said upwardly and downwardly facing tracks.

10. A printing press comprising a horizontal type-bed, a rocking impression-member, supporting rockers on the impression-member having bearing surfaces concentric with the bearing surface of the impression-member, upwardly facing supporting bearing surfaces formed on the bed adapted to be engaged by said supporting rockers, downwardly facing tracks supported on said bed adapted to engage the tops of said rollers, and means adapted to retain the ends of said rockers in engagement with said upwardly facing bearing surfaces of the bed after said rollers have passed beyond the limits of said downwardly facing rails.

In testimony, that I claim the foregoing as my invention I affix my signature in the presence of two witnesses, this 26th day of August A. D. 1909.

ROBERT O. VANDERCOOK.
